UNITED STATES PATENT OFFICE.

THOMAS H. MURPHY AND PHILIP M. ZOEGGELE, OF NEW BEDFORD,
MASSACHUSETTS.

DESIGN FOR A BREAD-PAN.

SPECIFICATION forming part of **Design No. 21,710**, dated July 12, 1892.

Application filed June 2, 1892. Serial No. 435,313. Term of patent 7 years.

To all whom it may concern:

Be it known that we, THOMAS H. MURPHY and PHILIP M. ZOEGGELE, citizens of the United States, and residents of New Bedford, 5 in the county of Bristol and State of Massachusetts, have invented a new and original Design for Inclosed Bread-Pans, of which the following is a specification, reference being had to the accompanying drawings.

Figure 1 represents a side view, Fig. 2 represents a plan view, and Fig. 3 represents an end view, of an inclosed bread-pan, showing the shape and configuration of our design.

In cross-section through the line $x x$ the

shape is nearly a square, the sides $a a$ being 15 slightly drawn in at the top. From this central point the sides $a a$ and the top b taper with curved lines to a small square $g g$ at either end of the pan, the bottom c being a straight line. 20

What we claim is—

The design for an inclosed bread-pan herein shown and described.

THOMAS H. MURPHY.
PHILIP M. ZOEGGELE.
